TOY TURTLE

Robert Zeidman, Mamaroneck, N. Y., assignor to Mail
Pouch Tobacco Co., Wheeling, W. Va., a corporation of Delaware

Application March 19, 1957, Serial No. 45,334

Term of patent 3½ years

(Cl. D34—2)

Fig. 1.

Fig. 2.

Fig. 3.

Figure 1 is a perspective view of a toy turtle, showing my new design, as seen from one side of the front thereof;

Figure 2 is a perspective view of the toy turtle, as seen from the other side of the front thereof; and

I claim:

The ornamental design for a toy turtle, substantially as shown.
